(57) **CLAIM**

The ornamental design for a hex driver flap wheel sander, as shown and described.

DESCRIPTION

FIG. 1 is a perspective view of a hex driver flap wheel sander showing our new design;

FIG. 2 is a front view of a hex driver flap wheel sander showing our new design;

FIG. 3 is a side view of a hex driver flap wheel sander showing our new design; and,

FIG. 4 is a back side elevation view of a hex driver flap wheel sander showing our new design.

The broken lines in the drawings depict portions of the hex driver flap wheel which form no part of the claimed design.
